UNITED STATES PATENT OFFICE.

LINCOLN HALL, OF LOS ANGELES, CALIFORNIA.

LABEL-FILE.

1,271,508.

Specification of Letters Patent.

Patented July 2, 1918.

Application filed March 28, 1917. Serial No. 158,035.

To all whom it may concern:

Be it known that I, LINCOLN HALL, a citizen of the United States, residing at Los Angeles, in the county of Los Angeles and State of California, have invented new and useful Improvements in Label-Files, of which the following is a specification.

This invention relates to a label file and particularly pertains to a file for holding 10 gummed labels and a shelf upon which said file is positioned.

It is the principal object of this invention to provide a file for gummed labels which will resiliently hold a pack of labels in an 15 upright position and will permit the foremost of said labels to be removed from the pack without danger of mutilating the labels.

Another object of this invention is to provide 20 a yieldable member for maintaining the labels in their upright position and which will permit the pack of labels to be moved in an unrestricted manner within the file without becoming disturbed and which will 25 hold the labels with slight pressure so that they will not become gummed to each other.

Another object of this invention is to provide 30 a label file which is neat and compact in its design and may be instantly positioned upon a filing shelf where it will be firmly and removably held.

Another object of this invention is to provide 35 adjustable means for accommodating labels of various dimensions without requiring the substitution of an entirely new file.

Another object of this invention is to provide 40 a label file with means whereby the various files may be closely positioned in relation to each other and the labels from the files readily removed without difficulty.

It is a further object of this invention to provide 45 a label file and a shelf therefor which may be readily made of simple sheet metal parts and which, when assembled, will present a neat and workmanlike appearance.

Other objects will appear hereinafter.

The invention is illustrated, by way of example, in the accompanying drawings in 50 which:

Figure 1 is a view in perspective illustrating one of the label files and the shelf upon which it is supported.

Fig. 2 is a view in transverse section as 55 seen through the label file and as disclosing the detail construction of the file as well as

the manner in which it interlocks with the shelf upon which it is mounted.

Fig. 3 is a view in end elevation illustrating a plurality of the files mounted in superimposed relation to each other and particularly discloses the ease with which the labels may be removed when the files are closely positioned.

Fig. 4 is a fragmentary view in section 65 and plan illustrating the yieldable means by which the label file is detachably held upon its shelf.

Referring more particularly to the drawings, 10 indicates a shelf, preferably formed 70 of sheet metal, and having an up-turned rear flange 11. This flange is provided as a means whereby the shelf may be secured to a suitable vertical mounting by means of wood screws 12. The shelf 10 is formed 75 with a continuation 13 which extends parallel to the shelf and is adapted to form a groove 14 along the forward edge of the shelf to detachably secure a label file 15 in position. In order to yieldably hold this file 80 when engaged by the extension 13 and seated within the groove 14, a flat spring 16 is secured against the flange 11 by one of the screws 12. This spring extends outwardly and exerts a yieldable pressure 85 against the back of the label file in a manner to hold it within the groove 14.

The label file is composed of a body plate 17 which is formed with an up-turned ledge 18 and a back-plate 19, all of which are integral with the floor of the file and are made of a single piece of sheet metal. The ledge is formed with forwardly extending tangs 20 which project into the shelf groove 14 and act to hold the body plate thereto. The 95 top marginal edge of the ledge 18 is formed with a rounded out-turned flange 21 which prevents the labels from becoming mutilated as they are drawn over the ledge, as would occur if this edge were sharp. The vertically extending back-plate 19 is formed with two obtrusions 22 which extend vertically and are adapted to slidably hold guard arms 23 and 24. These arms are thus adapted to be vertically adjusted and to permit their 100 forwardly extending horizontal arm portions to guard the label pack and at the same time permit the foremost labels to be removed from thereunder.

A pack of labels 25 is positioned upon the 110 floor of the file with their printed matter against the ledge 18. A follower plate 26 is

provided to bear against the back of the pack and yieldably held by means of a helical spring 27. It will be understood that other resilient means may be provided to hold the plate. However, in the present embodiment the spring 27 has been found to be desirable. This spring is of large diameter in relation to the width of the file and is formed of small wire which is not heavily tensioned. The forward end of the spring is permanently secured to the back of the follower plate, and the opposite end of the spring is permanently secured to the back-plate 19. Due to this construction the pack of labels may be moved beneath the guard arms 23 and 24 and when released will instantly be restored to a position against the ledge 18. In order to prevent the follower plate from binding when moved along the floor of the label file and beneath the guard arms 23 and 24, the upper and lower edges of the plate are turned over to provide a rounded surface adapted to bear against these members.

Due to the fact that labels are formed in various sizes, the present device has been designed to adjustably accommodate other sizes of labels than those shown in the drawings. The height of the label is accommodated by the vertical adjustment provided the label guard arms 23 and 24. The length is accommodated by horizontally adjusted arms 28 and 29. These arms are slidably secured within obtrusions 30, formed horizontally of the back-plate 19, and permit labels of various lengths to be positioned between them. The adjustable movement of the arm 28 is particularly indicated by dotted lines in Fig. 1.

Reference being had to Fig. 3 of the drawings, it will be seen that the label files are positioned closely together and in superimposed relation to each other. In order to permit the labels to be readily removed from the various files when thus disposed, an arcuate recess 31 is cut from the ledge 18 and a similar recess 32 cut from the floor of the file and the floor of the shelf upon which it is mounted. This permits the forefinger to be easily placed upon the pack of labels and the foremost withdrawn without difficulty.

In operation, the label file shelf is positioned against a suitable vertical support and there secured by means of the screws 12 which extend through the up-turned rear flange of the shelf. When mounted in position, one of the screws is placed through an opening in the flat spring 16 and holds it in a substantially horizontal plane extending along the flange 11. The file may then be detachably placed in position by placing the extension 34 of the rear flange 11 through a slotted opening 33 formed in the back-plate 19. When this has been accomplished the file may be pressed rearwardly against

the flat spring 16 and the tangs 20 permitted to seat within the groove 14 of the shelf. The file will thus be rigidly secured in a detachable manner. The pack of labels may then be placed within the file and will be held by the action of the spring 27 against the follower plate 26. After the labels have been so placed, the guard arms 23 and 24 may be adjusted to the height of the labels and the arms 28 and 29 adjusted to the length of the labels.

It will thus be seen that the label file here provided and the shelf upon which it is adapted to be mounted are both simple in their construction, compactly designed, and may be readily operated to accommodate and permit the removal of labels of various dimensions.

While I have shown the preferred construction of my label file and shelf therefor as now known to me, it will be understood that various changes in the combination, construction, and arrangement of parts may be made by those skilled in the art without departing from the spirit of my invention.

I claim:

1. A label file, comprising a file plate formed with up-turned front and back walls, the horizontal marginal edge of the front wall being curved outwardly, a follower plate adapted to slidably rest upon the file plate and secure a pack of labels against the front wall of said file plate, resilient supporting means secured to the follower plate and the back wall of the file plate in a manner to permit universal movement of said follower plate, adjustable means for accommodating labels of various heights, other adjustable means for accommodating labels of various lengths, a shelf, means whereby said file may interlock with and be supported by the shelf, and means for resiliently holding the file upon the shelf in a removable manner.

2. A label file comprising a shelf formed of sheet metal and having an up-turned rear flange and having a folded forward edge forming a groove, a flat spring extending forwardly from the rear flange, a body plate having an up-turned front ledge and an up-turned back plate; said back plate fitting against the spring; and tangs extending forwardly from the body plate into the groove at the forward edge of the shelf.

3. A label file comprising a shelf having an up-turned rear flange and a folded forward edge forming a groove; there being screw holes through the rear flange; a flat spring mounted against the rear flange, screws inserted through the spring and the flange, and a body plate having an up-turned forward ledge and an up-turned back plate and having tangs extending forwardly into the groove; so that by pressing the body plate backwardly the tangs will be disen-

gaged from the groove and the body plate may be removed.

4. A label file comprising a shelf of sheet metal having an up-turned rear flange and a folded forward edge; the central portion of the forward edge being cut away; a body plate having an up-turned forward ledge and an up-turned back plate; the central portion of the forward ledge being cut away to match the cut away portion in the shelf; a flat spring mounted against the rear flange; the up-turned back plate pressing against the spring; tangs extending forwardly from

the body plate into the groove, vertical bearings formed in the back plate, guard arms 15 slidably mounted in said bearings and extending forwardly above the top of the back plate, a follower plate mounted to slide upon the horizontal portion of the body plate below the guard arms, and a helical spring secured to the back plate and pressing against the follower plate.

5. A label file comprising a shelf of sheet metal having an up-turned rear flange and a folded forward edge; the central portion of the forward edge being cut away; a body plate having an up-turned forward ledge and an up-turned back plate; the central portion of the forward ledge being cut away to match the cut away portion in the shelf; a flat spring mounted against the rear flange; the up-turned back plate pressing against the spring; tangs extending forwardly from

In testimony whereof I have signed my name to this specification.

LINCOLN HALL.
